UNITED STATES PATENT OFFICE.

NEWTON J. DOUGLAS, OF WAUCOMA, IOWA.

GATE.

SPECIFICATION forming part of Letters Patent No. 354,107, dated December 14, 1886.

Application filed April 6, 1886. Serial No. 197,982. (No model.)

To all whom it may concern:

Be it known that I, NEWTON J. DOUGLAS, a citizen of the United States, residing at Waucoma, in the county of Fayette and State of Iowa, have invented certain new and useful Improvements in Gates, of which the following is a specification, reference being had therein to the accompanying drawings.

My invention relates to that class of farm-gates commonly known as "swinging" and "sliding" gates; and my object is to simplify the construction, reduce the number of parts, and provide a gate of this class that may be easily and cheaply set up; and the invention 15 consists in certain features of construction, hereinafter specified, and particularly pointed out in the claim.

Referring to the drawings, Figure 1 is a perspective of a gate constructed in accordance 20 with my invention, the same being shown partly open. Fig. 2 is a transverse longitudinal section of the same taken between the first and second rails. Fig. 3 is an enlarged detail showing the hanger employed; and Figs. 4, 5, 25 and 6, are details, hereinafter described.

Like letters indicate like parts in all the figures of the drawings.

A represents the usual longitudinal rails of a gate, and A' the usual tie-bars connecting the 30 same.

B represents the locking-post, and B' the hinge-post. The hinge-post B' is preferably rectangular in cross-section, and one of its corners, B², may be planed down for a purpose 35 hereinafter specified. A suitable distance up and down the post B', at that portion of the same that is planed, I form apertures B³, extending completely through said post.

C represents a bracket having the back portion, C', and the forwardly-projecting arms C²C³ perforated, as at C⁴C⁵, respectively, the former 40 perforation, C⁴, being considerably the larger. At the center of the back portion, C', of the bracket is an aperture, C⁶, and equidistant 45 therefrom are cast rearwardly-projecting lugs C⁷. The lugs C⁷ are adapted to register with the apertures B³ in the post B', and when so 50 registering and inserted therein the aperture C⁶ in the back portion, C', of the bracket is intended to register with an intermediate aperture, B⁸. Thus the bracket-fastenings, when mounted on a post, will occupy three holes, a

bolt, D, being adapted to pass through the apertures C⁶B³, and to the opposite side of the post B', where it is provided with a nut. It 55 will now be seen that the bracket may be secured at different points when thus mounted upon the post, and is held rigidly in place by the lugs C⁷ and bolt D.

E represents a bifurcated roller-support, at 60 the bottom of which is formed a lug, E', adapted to fit the aperture C⁶ of the bracket. The top of the bifurcated support is open, and within said bifurcations, at a suitable point, is mounted a roller, E², upon which the rail of the gate is 65 supported so as to slide.

The rail of the gate having been inserted between the bifurcations E³ and upon the roller E², the support E is inserted top end first through the aperture C⁶ of the bracket C, and the lug 70 E' then lowered down into the aperture C⁶, thus pivotally mounting the support with the gate therein in the bracket C. A pin or bolt, E⁴, passed through apertures E⁵ in the bifurcations E³, serves to retain the rails in position, 75 and also prevents the withdrawal of the support from the bracket.

It is readily apparent that the support and bracket may be cheaply and easily cast of metal, the lugs and apertures being formed 80 thereon, and the said bracket and roller support sold separately from any gate, and afterward put, with very little or no trouble, by the purchaser upon any gate adapted thereto.

From the above description the operation of 85 the invention is at once apparent, in that the gate may be slid back upon the roller a certain distance and then swung bodily to one side, as shown by dotted lines in Fig. 2. It is also apparent that by reason of the series of equidistant holes B³ the bracket, gate, and its roller-support may be adjusted at any desired elevation.

Heretofore the roller-supporting bracket has been cast with an arm projecting at such an 95 angle from the portion secured to the post as to bring the pivotal center of the roller-support outside of the post and opposite a corner thereof. I plane off one corner of the post, and then am enabled to use a stronger, more compact bracket, in that the pivotal center is nearer the portion of the bracket which is secured to the post. Bifurcated roller-supporting standards have heretofore been employed, but of 100

such form as to require the removal of the bracket or a portion thereof from the post to allow a separation of it from the post or gate, whereas by my construction the upper arm of the bracket is perforated to allow the support to be raised and removed. If the bolt E^4 is used, it is first removed; otherwise nothing prevents taking the gate and roller-support bodily away from the post.

10 Having described my invention and its operation, what I claim is—

The bracket C, having a bolt-aperture, C^6 , lugs C^7 , and the arms $C^8 C^9$, each having a bearing, $C^4 C^5$, respectively, the latter being smaller

than the former, and the roller-support having the bifurcations E^3 , adapted to fit the larger bearing, C^4 , and the pivot E' , adapted to fit the lower bearing, C^5 , and the bolt E^4 , the whole constructed and combined substantially as specified, and forming a complete gate-supporting device ready for attachment to a post by a single securing device.

In testimony whereof I affix my signature in presence of two witnesses.

NEWTON J. DOUGLAS.
